[57] CLAIM

The ornamental design for a convertible baby stroller, as shown and described.

DESCRIPTION

FIG. 1 is a front perspective view of a convertible baby stroller showing my new design;

FIG. 2 is a left side perspective view thereof, the right side view being a mirror image of that shown;

FIG. 3 is a front perspective view thereof;

FIG. 4 is a rear perspective view thereof, with the handle in an alternate position;

FIG. 5 is a rear perspective view of FIG. 4, with the front portion of the hood in folded condition;

FIG. 6 is a rear perspective view of FIG. 4, with the back rest in a raised position and the foot rest in a lowered position;

FIG. 7 is a left side elevational view thereof, with the back rest in a raised position and the hood assembly attached in place;

FIG. 8 is a right side elevational view of FIG. 7, with the handle in the first position;

FIG. 9 is a front perspective view of FIG. 7;

FIG. 10 is a right side elevational view of FIG. 8, with the hood assembly removed; and

FIG. 11 is a front perspective view of FIG. 10.
